(57) **CLAIM**

The ornamental design for a tool support clip, as shown and described.

DESCRIPTION

FIG. 1 is a right side perspective view of a first embodiment of the tool support clip of the present invention showing the Applicant's new design;
FIG. 2 is a front elevation view of the tool support clip of FIG. 1;
FIG. 3 is a rear elevation view of the tool support clip of FIG. 1;
FIG. 4 is a left side elevation view of the tool support clip of FIG. 1;
FIG. 5 is a right side elevation view of the tool support clip of FIG. 1;
FIG. 6 is a top plan view of the tool support clip of FIG. 1;
FIG. 7 is a bottom plan view of the tool support clip of FIG. 1;
FIG. 8 is a front elevation view of the tool support clip of FIG. 1 shown in use secured in a pocket supporting a hammer;
FIG. 9 is a front elevation view of the tool support clip of FIG. 1 shown in use secured to a belt supporting a hammer;
FIG. 10 is a right side perspective view of a second embodiment of the tool support clip of the present invention showing the Applicant's new design having a coated or covered lower section;
FIG. 11 is a front elevation view of the tool support clip of FIG. 10;
FIG. 12 is a rear elevation view of the tool support clip of FIG. 10;
FIG. 13 is a left side elevation view of the tool support clip of FIG. 10;
FIG. 14 is a right side elevation view of the tool support clip of FIG. 10;
FIG. 15 is a top plan view of the tool support clip of FIG. 10; and,
FIG. 16 is a bottom plan view of the tool support clip of FIG. 10.
The broken line showing the pocket and hammer in FIG. 8 and the belt and hammer in FIG. 9 is for illustrative purposes only and forms no part of the claimed design.
